REPLENISHING MECHANISM FOR LOOMS
George Cadorette, Hopedale, Mass., assignor to Draper
Corporation, Hopedale, Mass., a corporation of Maine
Filed May 14, 1962, Ser. No. 194,584
5 Claims. (Cl. 139—257)

This invention relates to looms for weaving and, in particular, to an automatic replenishing mechanism for removing the tip or filling bunch of yarn from the end of a bobbin to be transferred to a shuttle and for holding, releasing and disposing of the filling end and tip bunch.

It is the general object of the invention to provide an easily adjustable releasing mechanism to allow the disposition of the tip bunch and filling end of yarn at a definite point in the transfer cycle.

It is a further object to provide a mechanism to release at a predetermined position the clamping effect of the extractor jaws and the clamping plate, they having completed the act of removing from the next bobbin to be transferred the tip bunch of yarn and filling end.

It is a more specific object of the invention to provide a control mechanism to act upon the extractor and clamping plate whose action was initiated, upon indication of exhaustion of filling on the bobbin in a shuttle, by movement of the transfer parts which also actuate a cam operated mechanical means causing the extractor jaws to retire from their position over the bobbin tip, thereby removing the tip bunch of yarn and holding it secure with the aid of the clamping plate. After a predetermined number of picks by the loom, the extractor mechanism is allowed to move in the opposite direction toward the tip of the next to be transferred bobbin. As the extractor starts the return motion, the present invention by a simple inclined cam member causes the extractor jaws and the clamping plate to separate and release the filling end and tip bunch so as to be removed by the filling end control hook.

Other objects will become apparent from the following more detailed disclosure.

An improved method for the removal of the tip bunch from bobbins during transfer thereof into a shuttle has recently been disclosed wherein any commonly known method for indicating the necessity for bobbin transfer also actuates a cam driven linkage to cause a pivotally mounted extractor arm to move from its first stationary position surrounding the tip end of the ingoing bobbin to a second stationary position at the outward end of its arc of movement. Upon an indication that a transfer of bobbin has been made, the extractor arm with its extracting mechanism, which consists of a pair of jaw members and a clamping plate, moves back toward its first-mentioned position. Just prior to the end of the return motion a stop plate causes the clamping plate to separate from the jaw members and the tip bunch is released. One such extracting mechanism is disclosed in U.S. Patent No. 3,023,788 wherein the clamping plate is separated from the jaw members by striking a stop plate for the double purpose of releasing the held tip bunch and to be in position to receive another tip bunch upon transfer of the bobbin next in line.

According to the present invention, an improved mechanism has been devised for effecting the controlled release of the filling end and tip bunch at a greater distance from the end of the next to be transferred bobbin than has been previously possible. It has been found that by releasing the tip bunch at the end of the inward movement by the extractor there are two undesirable contingencies. First, the tip bunch may fall perpendicularly and be drawn into the open shed causing a cloth defect. Second, the tip bunch may not be released but remain in the extractor and accumulate with one or more other tip

2

bunches until their combined weight causes them to fall and be carried into the shed. In order to release the tip bunch from the extractor in a position where it will not be drawn into the open shed, this invention discloses the combination of a filling clamping and an angularly inclined cam member adjustably adapted to act against the filling clamp effecting release of the tip bunch so that it may be cleared away by the filling end control hook. Since the tip bunch is released from the extractor mechanism at an outward position from the end of the ingoing bobbin, the tip bunch does not fall upon or near the shuttle, so it is not drawn into the cloth. There is also more time for the filling end control hook to act in disposing of the loose end of filling and tip bunch.

The invention will be described in greater detail by reference to the accompanying figures of drawing, wherein:

FIG. 1 is a perspective view of the replenishing side of a loom having the invention applied thereto;

FIG. 2 is a plan view of the invention;

FIG. 3 is a perspective front elevation showing the relationship with the next to be transferred bobbin; and

FIG. 4 is a perspective front elevation in partial section.

In FIG. 1 a loomside 11 supports the bobbin replenishing mechanism which includes an inclined chute 12 through which bobbins move by gravity to a transfer position. An extractor arm 13 is pivotally mounted at one end 14 to an L-shaped bracket 15 which is attached to the side of the chute at 16. A linkage member 17 connects the extractor arm to an extractor arm lever 18 which is pivoted at 18' intermediate its ends. To the lower part of the lever, a stud 19 is adapted to move a cam follower 20 in an arc to engage the cam 21 upon call for replenishment to transfer a bobbin in a known manner as cited in U.S. Patent No. 3,023,788.

To the forward end of the extractor arm 13 is positioned the extractor mechanism generally designated 22 as shown in FIG. 3, consisting of a pair of jaw members 23 and 24 and a clamping plate 25 pivotally mounted at 26 which are biased toward each other by a coil spring 27. Fixedly attached to the pivoted end of the clamping plate 25 and held substantially at right angle thereto is formed a bell crank type member consisting of two opposed parallel side walls 28 and 29 interconnected laterally by a top surface member 30.

Extending through and at the extreme outside end of the sidewall 28 and parallel to the top surface 30 is a cam follower pin 31. This pin is positioned so as to raise the top surface plate 30 and, in so doing, move the clamping plate 25 away from the extractor jaws 23 and 24.

Reference is now made to FIGS. 1 and 3 where a cam support 32 is slidably adjustable on a fixed rod 33. Adjustment is made and held secure by any regular means such as a nut and bolt 34 in the lower portion of the cam support. Through the upper portion of the cam support 32 is inserted a rod 35 made free to rotate, but held from lateral movement by a means such as a fixed washer 36.

The inner end of rod 35 is secured to the edge of a flat surfaced cam member 37, as shown in FIG. 2, and is pivotally mounted to be biased by a coil spring 38 angularly inclined downward toward the outside of the loom. As the cam follower pin 31 passes up the inclined surface of cam 37 and reaches the axis of cam movement at the rod 35, further movement of the pivoting cam is limited by a stop member or pin 39. FIG. 3 illustrates a bobbin B and tip bunch 40.

A pin 41 is fixed to the side of the clamping plate 25 and is adapted to engage a plate 42 fixed to the side of the chute 12 so as to maintain the clamping plate out of engagement with the extractor jaws 23 and 24 when the latter are in position over the tip of the bobbin, but which

pin releases the clamping plate as soon as the extractor swings outwardly to remove the tip bunch.

In operation, when need for bobbin replenishment is signaled by the loom feeler motion (not shown), the stud 19 makes a partial revolution in a counterclockwise direction as seen from above. This movement places the cam follower 20 in line with the face of cam 21, also moving in a counterclockwise direction. As the cam face rises, the extractor arm lever 18 pivots and draws the extractor arm 13 through its outward arc of movement together with the extractor mechanism 22.

The extractor draws the tip bunch of filling yarn 40 from the bobbin B and the tip bunch is held by the pressure of the clamping plate 25 against the extractor jaws 23 and 24. During this direction of movement, the cam follower pin 31 passes ineffectually under the cam 37 as illustrated in FIG. 4.

When transfer of the new bobbin has been made, the extractor arm 13 and the extractor mechanism 22, still retaining its hold on the tip bunch 40 which had been removed from the previous bobbin, starts a return motion toward the tip of the next to be transferred bobbin. As this return motion starts, the cam follower pin 31 follows the inclined surface of cam 37, see FIG. 2. This raises the top surface member 30 and pivots the clamping plate 25 away from the extractor jaws 23 and 24 thus releasing the tip bunch as in FIG. 3, solid line drawing.

As the cam follower pin 31 passes over the inner end of cam 37, the clamping plate and extractor jaws are again pressed together. They then reopen as the extractor jaws pass over the tip of the new bobbin as in the dotted line drawing of FIG. 3. They are held in this open position for the second time in order that when the signal for transfer is made, the new tip bunch will be extracted and held, thus starting a second cycle as before.

While one embodiment of the invention has been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

I claim:

1. In combination in a loom for weaving, a bobbin feeding means for retaining and presenting for transfer to a loom shuttle a supply of bobbins having filling wound thereon an end of which is wound in the form of a tip bunch adjacent the bobbin end, an extractor arm movable endwise toward and away from the end of a bobbin to be transferred, a gripping means attached to the end of said arm which comprises a pair of jaw members biased toward each other and defining an opening therebetween, a clamp pivoted at one of its ends and biased

toward said opening, the improvement which comprises a first means effective to move said clamp away from said jaw members during movement of said extractor arm toward the end of a bobbin to be transferred, and a second means later similarly effective upon said clamp when said jaw members are in position over said bobbin end.

2. In combination in a loom for weaving, a bobbin feeding means for retaining and presenting for transfer to a loom shuttle a supply of bobbins having filling wound thereon an end of which is wound in the form of a tip bunch adjacent the bobbin end, an extractor arm movable endwise toward and away from the end of a bobbin to be transferred, a gripping means attached to the end of said arm which comprises a pair of jaw members biased toward each other and defining an opening therebetween, a clamp pivoted at one of its ends and biased toward said opening, the improvement which comprises an angularly inclined cam member effective to move said clamp away from said jaw members during movement of said extractor arm toward the end of a bobbin to be transferred, and a second means later similarly effective upon said clamp when said jaw members are in position over said bobbin end.

3. In combination in a loom for weaving, a bobbin feeding means for retaining and presenting for transfer to a loom shuttle a supply of bobbins having filling wound thereon an end of which is wound in the form of a tip bunch adjacent the bobbin end, an extractor arm movable endwise toward and away from the end of a bobbin to be transferred, a gripping means attached to the end of said arm which comprises a pair of jaw members biased toward each other and defining an opening therebetween, a clamp pivoted at one of its ends and biased toward said opening, the improvement which comprises a pivotally mounted, angularly inclined cam member effective to move said clamp away from said jaw members during movement of said extractor arm toward the end of a bobbin to be transferred, and a second means later similarly effective upon said clamp when said jaw members are in position over said bobbin end.

4. The combination as recited in claim 3 which further includes a stop member for limiting movement of said cam member in one direction, and spring means effective to bias said cam toward said stop member.

5. The combination as recited in claim 3 wherein said clamp includes a bell crank member adapted to be acted upon by said inclined cam member to cause said clamp to be moved away from said jaw members.
